US0D1015341S

(12) United States Design Patent (10) Patent No.: US D1,015,341 S
(45) Date of Patent: * Feb. 20, 2024

(54) DISPLAY OR PORTION THEREOF WITH
GRAPHICAL USER INTERFACE

(71) Applicant: Apple Inc., Cupertino, CA (US)

(72) Inventor: Graham R. Clarke, Scotts Valley, CA (US)

(73) Assignee: Apple Inc., Cupertino, CA (US)

() Term: 15 Years

(21) Appl. No.: 29/787,300

(22) Filed: Jun. 5, 2021

(51) LOC (14) Cl. 14-04

(52) U.S. Cl.

USPC D14/485; D14/488

(58) Field of Classification Search

USPC D14/485-495

CPC G06F 3/048-04897

See application file for complete search history.

(57) CLAIM

The ornamental design for a display or portion thereof with graphical user interface, as shown and described.

DESCRIPTION

1 Claim, 1 Drawing Sheet
